(57) **CLAIM**

The ornamental design for a slotted calendar slide, as shown and described.

DESCRIPTION

FIG. 1 is back perspective view of a first embodiment of a slotted calendar slide according to this invention shown broken away to indicate indeterminate length;

FIG. 2 is a front perspective view of the slotted calendar slide of FIG. 1;

FIG. 3 is an enlarged partial view of the slot and surrounding portion of the calendar slide of FIG. 1;

FIG. 4 is a front view of the calendar slide of FIG. 1;

FIG. 5 is an end view of the calendar slide of FIG. 1;

FIG. 6 is a back view of the calendar slide of FIG. 1;

FIG. 7 is a top view of the calendar slide of FIG. 1;

FIG. 8 is a bottom view of the calendar slide of FIG. 1;

FIG. 9 is a back perspective view of a second embodiment of a slotted calendar slide according to this invention shown broken away to indicate indeterminate length;

FIG. 10 is a front view of the calendar slide of FIG. 9;

FIG. 11 is an end view of the calendar slide of FIG. 9;

FIG. 12 is a back view of the calendar slide of FIG. 9;

FIG. 13 is a top view of the calendar slide of FIG. 9;

FIG. 14 is a bottom view of the calendar slide of FIG. 9;

FIG. 15 is a back perspective view of a third embodiment of a slotted calendar slide according to this invention shown broken away to indicate indeterminate length;

FIG. 16 is a front view of the calendar slide of FIG. 15;

FIG. 17 is an end view of the calendar slide of FIG. 15;

FIG. 18 is a back view of the calendar slide of FIG. 15;

FIG. 19 is a top view of the calendar slide of FIG. 15; and,

FIG. 20 is a bottom view of the calendar slide of FIG. 15.
